SANITARY FITTING FOR THERMOMETER BULBS

Alphonso Noble, Naugatuck, Conn., assignor to
The Bristol Company, Waterbury, Conn., a corporation of Connecticut

Application December 15, 1938, Serial No. 245,884

3 Claims. (Cl. 285—177)

This invention relates to a fitting or mounting for thermometer bulbs, and more especially to a readily releasable and replaceable fitting of the above nature suitable for use in dairies and other places where sanitary features are of paramount importance.

The extreme cleanliness demanded of equipment used in modern dairy practice requires that all parts of equipment coming in contact with milk being processed not only present no crevices or interstices wherein foreign matter may lodge, but that they be subject to easy and rapid disassembly for cleaning and sterilization, and to equally easy re-assembly for service.

15 With the above requirements in view, it has been customary to provide the bulbs of recording and controlling thermometers used in dairy work with threaded fittings in the forms of unions or stuffing boxes which may readily be sterilized when dismantled. Such a device is shown in U. S. Letters Patent No. 1,828,170 issued to C. W. Bristol October 20, 1931, and embodies a metallic fitting adapted to retain a thermometer bulb in operating position, and to be released by the unscrewing of a single thumb nut.

It is an object of the present invention to provide an improved fitting of the above general nature, in which the complete clamping may be effected by a partial turn of a rotatable clamping member without the possibility of over-tightening, and which fitting may be similarly released.

A further object of the invention is found in the provision of a device of the above nature in which sanitation is facilitated by the absence of irregular projecting parts or crevices.

A still further object is found in the provision of such a device in which a leak-proof assembly is not dependent upon the engagement of highly-finished metallic parts.

In carrying out the invention, a ferrule and a clamping element are provided and designed to fit over the thermometer bulb, each being provided with a cylindrical bore having at the inner end a conical tapered section, and the clamping element being adapted to be inserted into the bore of the ferrule and to be locked thereto to hold and compress between the said tapered sections a washer of resilient material for providing a liquid-tight engagement with all the surface it touches.

The nature of the invention, however, will best be understood when described in connection with the accompanying drawings, in which:

55 Fig. 1 is a front elevation, partly in longitudi-

nal section, of a fitting embodying the invention and assembled with a thermometer bulb in place.

Figs. 2 to 4, inclusive, are views, in side elevation, showing the various elements of the novel fitting, Fig. 2 showing the clamping element and Fig. 4 the ferrule thereof, while Fig. 3 shows a resilient washer held between the said ferrule and clamping element.

Fig. 5 is a front elevation, partly in longitudinal section, illustrating a modification.

Fig. 6 is a similar view of a further modification; and Figs. 7 and 8 are, respectively, a fragmentary plan view and a fragmentary side elevation and longitudinal section thereof.

Referring to the drawings, 10 designates a thermometer bulb of the conventional form used in dairies, and consists of a hollow cylindrical metallic closed casing containing an expandible or volatile fluid. This casing is connected by means of a capillary tube 11 to a pressure-responsive member (not shown in the drawings, but well known in the art of temperature measurement) and whereby variations in pressure of the fluid contained within the bulb 10, due to changes in temperature of the fluid in which the bulb is immersed, may be utilized to provide a measure of, or to command an automatic control of, the said temperature.

A ferrule member 12 is provided with a conical face 13 adapted to fit a suitably formed face of a standard dairy fitting (not shown in the drawings) and the said ferrule is adapted to be clamped to the standard fitting by means of a nut 14 to form therewith a sanitary union of a type well known in dairy practice and forming no part of the present invention. Formed within the ferrule member 12 is a cylindrical recess 15 of a diameter materially greater than that of the bulb 10, and provided at its inner end with a conically tapered section 16 leading to a feather-edged aperture 16' having a diameter substantially equal to that of the bulb 10. Toward the outer end of the recess 15 are formed in the material of the ferrule 12 diametrically opposed slots 17, directed at first axially, then curving to a circumferential direction, and attaining a slightly hook-shaped conformation, as shown in Fig. 1.

A clamping member or gland 18 has its one extremity in the form of a wing-nut, and is of an outer cylindrical surface having a diameter such as to provide a free-running fit within the recess 15 in the ferrule 12. A cylindrical bore 18' therethrough is made of a diameter to provide a sliding fit on the bulb 10; and, at the extremity op-

10

55

posed to that having the wing-nut conformation, there is provided a conically tapered recess **19** similar in dimensions to those of the tapered section **16** within the ferrule **12** and adapted to be **5** juxtaposed to the section **16**. Diametrically opposed on the outer surface of the cylindrical part of the member **18** are disposed outwardly projecting pins **20** adapted to enter the slots **17** when the clamping member **18** is inserted within the **10** ferrule **12**; and, as the two members are relatively rotated, the said pins engage the circumferential parts of said slots, forming therewith a bayonet joint and drawing the said members together in clamping engagement. Of course, the **15** arrangement of pins and slots may be the reverse, the latter then being provided in the gland **18** with the cooperating pins projecting from the ferrule **12**.

A washer **21**, shown in Fig. 3, is formed of resilient material, such as neoprene, cork, or paraffined paper, not subject to ready attack or contamination by milk, with opposed conical surfaces adapted to be engaged by the corresponding surfaces **16** and **19**, respectively, of the ferrule and the clamping member. This washer, **25** also, is provided with a central opening **22** designed to fit closely the cylindrical surface of the bulb **10**, so that when the washer is placed upon the bulb and clamped between the said conical **30** surfaces of the ferrule and the gland respectively, it will be compressed into said liquid-tight engagement with all surfaces which it contacts and will provide a secure fastening for the bulb without exposing any appreciable surface to contact **35** with the milk in which the bulb may be immersed. The feather edge **16'** to which the section **16** is reduced eliminates the possibility of lodgement of foreign matter at this point in the assembly. As these washers are obtainable at a **40** relatively low cost, they may be economically discarded after once being used.

In the modification illustrated in Fig. 5, a gland member **25** bears upon a similar washer **26** to press the same against the bulb **27** and a feather edge **28** of a ferrule **29**, this being accomplished by providing the latter with an external thread **30** engaged by the internal thread of a sleeve **31** depending from a clamping member **32** separate from the gland **25**. The said **45** clamping member is rotatably mounted upon the bulb **27**, being manipulated by the integral wings **33**, and has an inner shoulder **34** to engage the gland **25** and press it into contact with washer **26**.

Or, as indicated in Figs. 6 to 8, inclusive, the **50** separate clamping member **35** may be wedged against the gland **36** through engagement of headed pins or studs **37** extending upwardly from the ferrule **38** and diametrically disposed on the

top of said ferrule. The studs pass into corresponding and diametrically disposed keyhole slots **39** of the clamping member and having a sloping surface **40**, adapted for engagement with the respective heads of studs **37** as the clamping member is correspondingly rotated. By this expedient, the gland **36** is accordingly advanced to exert pressure upon the washer **41**, or this pressure is released for disassembling the fitting. **5**

I claim:

1. Means for mounting a thermometer bulb having contact with a liquid, said means including a pair of bored coaxial clamping members surrounding a portion of the bulb, one member fitting slidably within the other and engaged therewith by a clamping joint to slide axially the one member relatively to the other, and the bores of both members affording respective juxtaposed opposed recesses, together with a resilient washer located within the said recesses, adapted to be clamped between said members and thereby forced into liquid-tight engagement with the surface of said bulb. **10**

2. Means for mounting a thermometer bulb having contact with a liquid, said means including a pair of bored coaxial clamping members surrounding a portion of the bulb, one member fitting slidably within the other and engaged therewith by a clamping joint to slide axially the one member relatively to the other, and the bores of both members affording respective juxtaposed opposed conical recesses with the recess of the innermost member tapering to a feather edge having a diameter providing a sliding fit for said bulb, together with a resilient washer located within the said recesses, adapted to be clamped between said members and thereby forced into liquid-tight engagement with the surface of said bulb and the feather edge. **25**

3. Means for mounting a cylindrical thermometer bulb in contact with a liquid, including clamping members surrounding said bulb and having therein opposed recesses disposed coaxially with said bulb, said members forming a stuffing box adapted in response to clamping forces to exert centrally directed radial forces on the contents of the stuffing box, together with a washer of resilient material located between said clamping members about the bulb with opposite faces in contact with the respective walls of said recesses and to be clamped into intimate engagement with the cylindrical surface of said bulb, and means to slide the one clamping member axially relatively to the other and including a manually operable element mounted over the bulb **35** and in threaded engagement with the other clamping member. **40**

ALPHONSO NOBLE.
